UNITED STATES PATENT OFFICE.

FRANK F. WOLF, OF BUFFALO, NEW YORK, ASSIGNOR TO RICE & ADAMS CORPORATION, OF BUFFALO, NEW YORK.

JET BOX FOR BOTTLE-WASHING MACHINES.

Application filed February 10, 1923. Serial No. 618,362.

This invention relates to jet or spray boxes of the kind used in connection with bottle washing machines, particularly with machines in which the bottles are washed 5 while contained in crates or cases.

The objects of this invention are to provide a jet box having drain openings to permit a free discharge of water from the top surface thereof and thereby prevent the 10 water from collecting on the top surface in such a manner as to impede the discharge of water to the bottles; also to so construct the jet box that the water will be uniformly distributed throughout the same, so that the 15 water will be discharged at substantially equal pressure from all of the discharge orifices of the box; also to so construct the jet box that the foreign matter in the liquid will not tend to obstruct the flow of liquid 20 through the orifices; also to provide the box with removable parts or caps which are formed to collect foreign matter from the liquid supplied to the jet boxes and which when removed permit ready access to the 25 interior of the jet boxes; also to improve the construction of jet boxes in other respects hereinafter specified.

In the accompanying drawings:

Fig. 1 is a top plan view of a jet box embodying the invention.

Fig. 2 is a side elevation thereof.

Figs. 3 and 4 are longitudinal sectional elevations thereof on lines 3-3 and 4-4 respectively, Fig. 1.

Fig. 5 is an end elevation thereof showing one of the end caps removed therefrom.

Fig. 6 is a transverse sectional elevation thereof on line 6-6, Fig. 1.

Fig. 7 is a sectional view thereof on line 40 7-7, Fig. 2.

The jet box shown in the accompanying drawings is intended to operate simultaneously on two crates or cases containing either quart or pint bottles, but it will be 45 understood that the invention may equally well be used in connection with jet boxes which operate on only one crate at a time, or on one size of bottles.

The jet box embodying the invention 50 which is shown in the drawings includes a hollow casting having a central supply tube or passage A which extends transversely of the jet box and is preferably provided at one end with a flange or other means a for connecting the jet box with a supply of

liquid and at the other end with a removable plug a' which facilitates the cleaning of this passage. The central passage A connects with a plurality of spray tubes or passages B which project from opposite sides 60 of the central supply passage A and which are spaced apart to provide apertures or spaces C through which the water running from the bottles may be discharged. The spray tubes are preferably arranged to receive liquid from the upper portion of the supply passage, so that foreign matter carried into the jet box due to the recirculation of the washing fluid will not tend to close the discharge orifices in the spray pipes. 65 The closed end of the supply passage is preferably provided with a depressed portion or wall a' which serves to collect foreign matter from the fluid. The spray tubes B are provided with substantially flat 70 upper faces in which the discharge orifices are arranged. These orifices are preferably so positioned as to project jets of water or other fluid into the bottles and since the jet boxes must be adapted to operate on either 75 pint or quart bottles, two sets of discharge orifices are provided, a set of orifices b serving to project jets of liquid into quart bottles, which are generally arranged in cases or crates containing a dozen bottles, and the 80 orifices b' serving to project liquid into smaller bottles, which are generally arranged in cases containing twenty bottles. The spray tubes B, owing to the necessity 85 for arranging the discharge orifices in definite positions on the jet boxes, may be made of different shapes in cross section, depending upon the location of the orifices, and consequently the spaces C between the adjacent spray tubes also vary in shape, as is 90 indicated clearly in Figs. 1 and 6. By providing spaces or openings in the jet box, the water discharged from the bottles upon the flat upper face of the jet box will be quickly 95 discharged or drained therefrom and thus offer very little resistance to the flow of liquid through the orifices. This arrangement, therefore, greatly increases the efficiency of jet boxes of this type in that very little of the force of the water is lost in 100 overcoming the resistance of a layer of water on the jet boxes, and consequently the force thus made available serves to more thoroughly cleanse the bottles.

The outer ends of the spray tubes B are 110

preferably formed integral with connecting members D, which also serve to strengthen the jet boxes by forming a rigid connection between the ends of the spray tubes. The connecting end members D are preferably open at the opposite ends of the jet boxes and are adapted to be closed by means of removable caps or end pieces E, which are preferably arranged at an inclination. 5 These caps are hollow and trough shaped in cross section and may be secured to the ends of the jet boxes in any suitable or desired manner, for example, by means of machine screws or the like e passing through 10 the end pieces and engaging in threaded holes e' in the connecting end members D. The trough shaped portions e² of the caps or end members E, due to the inclined arrangement of the end caps, extend below the spray tubes B and serve to collect foreign matter which may be introduced into the jet boxes with the washing or rinsing liquid. It has been found that most of the foreign matter found in rinsing or washing water 15 has a tendency to pass lengthwise of the spray tubes B to the ends thereof and to become deposited in the trough shaped portions of the caps, where it can be conveniently removed by detaching the caps from the jet boxes. The caps may, if desired, also be provided with plugs f which can be removed to permit the accumulation of foreign matter in the trough shaped portions in the caps E to be discharged from the jet boxes without removing the caps therefrom. When the caps E are removed from the jet boxes, the interiors of all of the spray tubes B are rendered readily accessible so that 20 foreign matter may be removed therefrom by means of the cleaning brush or other device. By arranging each end cap E at an inclination to the jet box, these end caps can be readily removed even if the jet boxes are arranged close together in a machine or 25 are otherwise located so as to prevent ready access to the ends of the box, and this inclined arrangement also facilitates the insertion of brushes or other cleaning devices when the end caps are removed and when 30 the jet boxes are arranged in close proximity to each other.

The depressed end a² of the central supply passage can be readily opened by means of the plug a' to permit foreign matter to be removed from the jet boxes, and by arranging the end caps E at an inclination so that the trough shaped portions thereof extend below the spray tubes B, it will be readily seen that the tendency of any foreign matter entering into these troughs would be to remain in the troughs. The foreign matter is thus kept from the orifices and as a result of the construction described

the jet boxes are less apt to become clogged with foreign matter than similar devices heretofore made. The trough shaped end caps E, however, also serve to equalize the pressures in the various spray tubes B so that all of the jets will be discharged from the boxes at substantially the same pressure. 70

I claim as my invention:

1. A jet box including a central supply passage, a group of tubes extending outwardly from opposite sides of said supply passage and provided in their upper portions with orifices, said tubes being spaced apart to permit liquid returning to the upper face of the box to be discharged therefrom, parts connecting the ends of said tubes, a hollow cap extending across and closing the ends of each group of tubes and permitting liquid to flow from one tube to another, said caps being removable for rendering the interiors of said tubes accessible. 75

2. A jet box having in its upper face orifices for the discharge of liquid, a liquid inlet in said box, said box being hollow and having openings therethrough for the discharge of liquid returned to the upper face of the box, and a cap removably secured to the end of said box which is opposite to said inlet and having a trough shaped portion extending downwardly from said box and adapted to collect foreign matter from the liquid supplied to said box. 80

3. A jet box having in its upper face orifices for the discharge of liquid, a liquid inlet in said box, said box being hollow and having openings therethrough for the discharge of liquid returned to the upper face of the box, a cap removably secured to the end of said box and having a trough shaped portion extending downwardly from said box and adapted to collect foreign matter from the liquid supplied to said box, and a plug in said cap which is removable to permit the material in said trough shaped portion to be flushed out by the liquid passing through said box from said inlet. 95

4. A cast metal jet box including a central supply passage having an inlet end for liquid and having a depressed portion at the other end thereof in which foreign matter may collect, means for obtaining access to the interior of said depressed portion, spray tubes extending outwardly from said supply passage, a channel shaped member removably secured to the jet box and connecting the ends of said tubes, said channel shaped member extending below said spray tubes to collect foreign matter from the liquid supplied to the jet box and means whereby the collected matter may be flushed from said channel member by the liquid flowing through said tubes. 100
